(57) **CLAIM**

The ornamental design for a removable fifth string capo for a banjo, as shown and described.

DESCRIPTION

FIG. 1 is a top perspective view of a removable fifth string capo for a banjo, showing my new design;

FIG. 2 is a top plan view thereof;

FIG. 3 is a bottom plan view thereof;

FIG. 4 is a side elevation view thereof;

FIG. 5 is a front elevation view thereof;

FIG. 6 is a rear elevation view thereof; and,

FIG. 7 is a top plan view of a removable fifth string capo for a banjo showing my new design with the banjo being shown by broken lines, which are for illustrative purposes only and forming no part of the claim.
